CLAIM

The ornamental design for a sorter drivable wheels, as shown and described.

DESCRIPTION

FIG. 1 is an isometric view of sorter drivable wheels in a straight configuration of the applicant's design;

FIG. 2 is a top view of FIG. 1;

FIG. 3 is a bottom view of FIG. 1;

FIG. 4 is a back view of FIG. 1;

FIG. 5 is a front view of FIG. 1;

FIG. 6 is a left side view of FIG. 1;

FIG. 7 is a right side view of FIG. 1;

FIG. 8 is an isometric view of FIG. 1 reconfigured into a circular configuration;

FIG. 9 is a top view of FIG. 8;

FIG. 10 is an isometric view of FIG. 1 reconfigured into a serpentine configuration;

FIG. 11 is a top view of FIG. 10;

FIG. 12 is an isometric view of FIG. 1 reconfigured into a triangular configuration;

FIG. 13 is a top view of FIG. 12;

FIG. 14 is an isometric view of FIG. 1 reconfigured into a rectangular configuration; and,

FIG. 15 is a top view of FIG. 14.

The broken lines are included for the purpose of illustrating portions of the sorter drivable wheels that form no part of the claimed design.

1 Claim, 15 Drawing Sheets
